(57) **CLAIM**

The ornamental design for a “holder,” as shown and described.

DESCRIPTION

FIG. 1 is a perspective view of a holder showing our new design;

FIG. 2 is a front elevational view of the holder of FIG. 1;

FIG. 3 is a top plan view of the holder of FIG. 1;

FIG. 4 is a left side elevational view of the holder of FIG. 1, the right side elevational view being a mirror image thereof;

FIG. 5 is a bottom plan view of the holder of FIG. 1;

FIG. 6 is a rear elevational view of the holder of FIG. 1; and, FIG. 7 is another perspective view showing our new design. The dashed lines are for illustrative purposes only and form no part of the claimed design.
